UNITED STATES PATENT OFFICE.

MILTON WHITEFORD, OF MANITO, ILLINOIS.

GATE LATCH AND SUPPORT.

Application filed August 4, 1925. Serial No. 48,125.

This invention relates in general to gates and more particularly to a latching and supporting means for swinging gates.

The object of the invention is to provide a latch which may be set to cooperate with the gate to secure the same in closed position irrespective of the direction in which the gate swings and which automatically latches the gate when the same is closed.

10 A further object is to provide a gate having these advantages and capacities and which aids the hinges in properly supporting the gate when the gate is closed.

15 A still further object is to provide a gate latch which may be readily released.

Another object is to provide a device of this character which is of simple and durable construction, reliable in operation and easy and comparatively inexpensive to manufacture.

20 Other objects and advantages reside in certain novel features of the construction, arrangement and combination of parts which will be hereinafter more fully described and particularly set out in the appended claims, reference being had to the accompanying drawings, forming part of this specification and in which:—

Figure 1 is a view in elevation showing 30 one embodiment of the invention,

Figure 2 is a fragmentary view in elevation showing the latch set to receive the gate, the gate being shown approaching closed position,

35 Figure 3 is a fragmentary view in elevation showing the latch as positioned when the gate is closed, and

40 Figures 4 and 5 are sectional views on lines 4—4 and 5—5 of Figs. 2 and 2 respectively.

45 Referring to the drawings the numeral 1 designates generally a gate which is supported for horizontal swinging movement on a post 2 by means of hinges 3 and 4.

50 The latch which constitutes the present invention is designated generally at 5 and is supported on a post 6 disposed opposite the post 2.

55 The latch 5 comprises a latching member consisting of a vertically disposed channel 7 mounted for sliding and rotary movement relative to its post 6. The channel 7 has a base or body portion 8 and side flanges 9. Brackets 10 and 11 are fastened to the body portion 8 of the channel. Rearwardly extending and vertically aligned apertures

ears 12 are integrally formed on the brackets 10 and 11 and in the apertures of the ears, rods 14 are slidably and rotatably fitted, the rods having studs 15 by which they are secured and supported on the posts 6. With this arrangement the channel is vertically slidably parallel to its post and rotatable about an axis parallel to its post.

60 A retractile coil spring 16 is provided and has its lower end connected as at 17 to the body portion of the channel and its upper end suitably fixed as by means of a connection 18 with an eye 19 formed on the lower end of the rod. The spring 16 is tensioned to lift the channel 7 upwardly as far as it may travel.

65 The channel 7 is designed to receive and hold the gate 1 in closed position irrespective of which way the gate may be swung. Means is provided to releasably hold the channel member in gate receiving position and this same means also serves to hold the gate closed and comprises pairs of holding members or plates designated at 20 and 21. 70 The plates 20 are fixed to the post 6 at one side and the plates 21 are fixed to the post 6 on the opposite side and in horizontal alignment with the plates 20. The members of each pair of plates are vertically spaced 75 so as to be cooperable with the projecting portions of the brackets 10 and 11. The bracket 10 has laterally extending projections 10^a and 10^b and the bracket 11 has similar projections 11^a and 11^b.

80 When the latch is set to gate receiving position the channel 7 is pressed down against the tension of the spring 16 and then rotated to one side or the other of the post depending on which way the gate swings. In Fig. 3 the channel is shown swung to the near side of the post with the projections 10^a and 11^a engaged beneath the plates 20. When the channel is pressed down and swung in the opposite direction 85 the projections 10^b and 11^b engage beneath the plates 21 but, of course, this is done only when the gate swings from the other side of the post to a closed position.

90 With the channel 7 positioned as shown in Figure 2 when the gate swings to closed position its free end portions 1^a strike one of the side flanges 8 of the channel to swing the channel about its rods 14 until the projections 11^a disengage the plates 20 whereupon the spring 16 lifts the channel to bring the backs of all of the projections of

the brackets 10 and 11 into engagement with the plates 20 and 21 to hold the channel against swinging movement in either direction and consequently to hold the gate in closed position. To release the gate the channel 7 must be pressed down against the tension of the spring 16 until the projections 10^a, 10^b, 11^a and 11^b are below the plates 20 and 21 when the channel may be swung on its rods to release the gate.

The side flanges 8 of the channel 7 are formed with transversely aligned openings 25 into any pair of which a cross pin 26 may be fitted and secured. The pin 26 is located to engage under a portion 1^b of the gate to lift the free end of the gate so as to relieve the gate and its hinges of strain and prevent sagging.

Rollers may be provided to reduce the friction between the projections and the plates and as illustrated, these rollers may comprise arms 27 fixed on the plates 20 and 21 and carry rollers 28 engageable with the projections.

One of the advantages of the gate latch and support resides in the fact that it will hold the gate in closed position irrespective of the distance that the gate swings above the ground.

I claim:—

1. A latch for a swinging gate comprising a latching member engageable with the gate, means for mounting the latching member for turning and sliding movement, means for holding the latching member against movement in one angular adjustment and in one phase of its sliding movement, means tending to urge the latch member to such phase, and means for releasably holding the latching member in gate receiving position when the latching member is set in another phase of its sliding adjustment and in another angular adjustment, and means on the latching member for lifting the free

end of the gate when the gate is latched 45 in closed position.

2. A latch for a swinging gate comprising an elongated and vertically disposed channel having its side flanges engageable with the free end of the gate for a substantial portion of the vertical extent thereof, means for mounting the channel for sliding and swinging movement, means connected with but separate from for releasably holding the channel in gate receiving position, and means for holding the channel in position to secure the gate closed.

3. A latch for a swinging gate comprising a channel engageable with the free end of the gate, means for mounting the channel for limited sliding and swinging movement, a spring for urging the channel upwardly, fixed holding plates, and projections on the channel engageable with the underside and front edges of the holding plates.

4. A latch for a swinging gate comprising a channel engageable with the free end of the gate, means for mounting the channel for limited sliding and swinging movement, a spring for urging the channel upwardly, fixed holding plates, projections on the channel engageable with the underside and front edges of the holding plates, and means on the channel for supporting the free end of the gate.

5. A latch for a swinging gate comprising a channel engageable with the free end of the gate, means for mounting the channel for limited sliding and swinging movement, a spring for urging the channel upwardly, fixed holding plates, projections on the channel engageable with the underside and front edges of the holding plates, said channel having a series of openings, and a cross pin selectively engageable with the openings and engageable with the gate to lift the same.

MILTON WHITEFORD.
